BARGE

Edgar T. Strom, Beulah, N. Dak.

Application August 21, 1947, Serial No. 769,898

5 Claims. (Cl. 298—20)

1

My invention relates to an improvement in barge wherein it is desired to provide a device capable of moving heavy loads of hay, straw, or the like, and including an unloading mechanism.

In the handling of hay, straw, and the like, it is normal practice to fill a wagon or rack, to transport this material to its destination and to remove the material and stack the same. In accomplishing this result it is necessary to handle the hay or straw several different times. It is a purpose of the present invention to provide a device capable of carrying a quantity of hay or straw sufficient in itself to build the stack by providing suitable unloading means. The stack may be formed in the barge and transferred onto the ground in stacked form.

It is the object of the present invention to provide a barge capable of hauling a considerable quantity of hay or straw and to provide an unloading mechanism by means of which this large quantity may be removed. At the same time, it is the purpose of the present invention to provide a device which will accomplish the desired result with a minimum of power and a maximum of efficiency.

A feature of the present invention lies in the provision of a barge supported by wheels located intermediate the ends of the barge and to provide a means of tilting the barge toward one end so as to reduce the power necessary to remove the stacked material from the barge. When the barge is held on an incline the stacked material may be transferred directly onto the ground without destroying the general shape of the stack.

A feature of the present invention lies in the provision of a means for tilting the barge without providing special power means to accomplish this result. My barge is provided with pivoted tilting legs which may be pivoted into contact with the ground. By moving the barge longitudinally these legs pivot toward vertical position, tilting one end of the barge without special hoisting mechanism for this purpose.

A feature of the present invention lies in the combination of a means for tilting one end of the barge upwardly and in providing a locking mechanism for holding the barge in tilted position. As a result once the barge is in tilted position the legs may be pivoted upwardly to allow movement of the barge in either direction while tilted.

A feature of the present invention lies in the provision of a barge having a tapered formation with the back end thereof wider than the front. This barge is also provided with an unloading member which is movable longitudinally of the barge to force the stacked material toward the rear end thereof. The wedge shape of the body allows the unloading member to work more effectively than would otherwise be possible.

An added feature of the present invention lies

2

in the provision of a barge having a tail gate supported by a slideable hinge arrangement. The gate is so arranged that one end thereof may be unhooked and the entire gate may be pivoted at right angles and slid along one side of the barge, being supported by the wall.

An added feature of the present invention lies in the provision of a barge which may be moved by a tractor or similar vehicle and which has incorporated therein an unloading device which is operable from the power take-off of the tractor. Thus the entire device may be actuated by power which is readily available.

These and other objects and novel features of my invention will be more clearly and fully set forth in the following specification and claims.

In the drawings forming a part of my specification:

Figure 1 is a side elevational view of a barge in unloading position showing the manner in which it is connected to a tractor or the like.

Figure 2 is a longitudinal section through the barge showing the construction thereof.

Figure 3 is a top plan view of the barge.

Figure 4 is an elevational view of the front end of the barge body.

Figure 5 is a bottom plan view of the barge.

Figure 6 is a detail view of a locking mechanism used in conjunction with the barge body.

The barge A includes a frame 10 having a front cross member 11, a center beam 12 and four spaced longitudinally extending beams or stringers 13, 14, 15, and 16. The outermost beams of the series are arranged somewhat wider apart at their rear ends than at their forward ends where they connect to the cross member 11. A cross brace 17 extends between the innermost stringers 14 and 15 to form a support for the drive shaft supporting mechanism.

A pair of longitudinally extending beams 19 and 20 are arranged in parallel spaced relation between the stringers 14 and 15. Cross members 21 connect the beams 19 and 20 at intervals and form bearings for the drive shaft 22. The forward end of the drive shaft 22 is connected through a universal joint 23 to a shaft 24 leading to a transmission 25. The rear end of the drive shaft 22 is connected through a universal joint 26 to a shaft 27 extending into a gear box 29.

The gear box 29 contains suitable bevel gears or the like to transmit motion from the shaft 27 to the right angularly extending shaft 30. The shaft 30 is supported by suitable bearings on the rear ends of the stringers 14 and 15.

The stringers 13, 14, 15, and 16 form a supporting frame for a flooring 31 forming the bottom of the barge A. Upright posts 32 extend upwardly from the outermost frame member 13, while similar posts 33 extend upwardly from the opposite frame member 16. The posts 32 and 33

60

support side walls 34 and 35 respectively. Side frame reinforcing rails 36 and 37 also connect the top ends of the posts 32 and 33 respectively. A vertically extending supporting post 39 extends upwardly from the cross member 11 at the front end of the body. A front wall 40 connects the foremost posts 32 and 33 of the side walls, forming a closed front end on the body. As best illustrated in Figure 4 of the drawings the posts 32 and the side wall 34 are somewhat higher than the posts 33 and the side wall 35 so that the front wall tapers from the wall 34 toward the wall 35. This provides a lower side on the barge which is useful when the barge is used in harvesting grain with a header. A pair of short shaft sections 41 and 42 are mounted in alignment near the forward end of the barge and at approximately the floor level of the barge.

Rollers or sprockets 43 and 44 are mounted on the shafts 41 and 42 respectively. Aligned sprockets 45 and 46 are mounted on the ends of the transverse shaft 30 at the rear end of the barge, which shaft is also at approximately floor level. The sprockets 43 and 45 support a chain 47, while the sprockets 44 and 46 support a chain 49.

A pusher member 50 in the form of a side plank is supported by triangular braces 51 and 52 in a generally vertical plane. These braces are connected at their ends to the chains 47 and 49 for movement therewith. The brace 51 is connected at its forward end 53 to one end of the chain 47 and is pivotally connected at its other end 54 to the other end of the chain 47. Similarly the brace 52 is connected at its ends 55 and 56 to the ends of the chain 49. Movement of the chains 47 and 49 thus moves the pusher toward one end or the other of the barge.

A pair of supporting wheels 57 are mounted at each end of the cross beam 12 to movably support the frame of the barge. In preferred form the beam 12 extends across the body slightly to the right of the center thereof so that if the weight of the body is equally distributed, the body will always tend to tilt forwardly. A substantially V-shaped draw bar 59 extends from a forward pivotal connection 60 forwardly of the barge body to a point just forwardly of the center of the body. The separated ends of the draw bar 59 are connected along aligned pivots 61 to the frame members 13 and 16. Thus the barge body may pivot about a horizontal axis relative to the draw bar. A shaft or bar 62 extending transversely of the draw bar is pivotally supported in spaced bearings 63 thereupon. An angle member 64 is secured to the shaft or bar 62 and extends upwardly therefrom. This angle member extends between the frame member 19 and the shaft 24 and extends upwardly adjacent the forwardly projecting bracket 65 on the front wall 40. The angle member 64 is held adjacent the bracket 65 by a U-shaped enclosure 66, best illustrated in Figure 3 of the drawings. As best illustrated in Figure 6 of the drawings a locking lever 67 is pivoted to the bracket 65 at 69. One end 70 of this lever engages in a selected aperture 71 in the angle member 64. The locking lever 67 is provided with a lug 72 thereon which prevents excessive pivotal movement of the lever. Thus when the locking lever 67 is engaged the body of the barge may be held in fixed relation to the draw bar 59.

A pair of legs 73 are pivotally supported along aligned pivots 74 on the undersurface of the frame members 13 and 16. Hook means 75 are

provided on the frame members for holding the legs 73 in generally parallel relation to the frame members 13 and 16. The legs 73 are foldable downwardly into contact with the ground and are of sufficient length to tilt the rear end of the barge against the ground before pivoting into vertical position.

The tail gate of the barge is formed as best illustrated in Figures 1 and 3 of the drawings. 10 The tail gate 76 includes a pair of spaced vertical supports 77 and 79 to which are attached transversely extending members 80 forming a rear closure. A chain 81 is loosely connected to the tail gate 76 by supporting loops 82. The ends 15 of the chain 81 are engageable with suitable catches 83 on opposite side walls of the body to hold the lower end of the tail gate in closed position. The tail gate 76 is supported by a transversely extending supporting bar or pipe 84 extending parallel to the cross members 80 and above the level thereof. Suitable straps 85 suspend the tail gate from the bar or pipe 84. When in closed position one end of the bar 84 is supported in a spring clamp 86 mounted at the 25 rear edge of the side wall 35 and by a freely supported pulley or roller 87 mounted at the rear end of a rail or pipe 89. The rail or pipe 89 is supported by suitable brackets 90 to the outer surface of the side wall 34 of the barge.

30 When it is desired to move the tail gate 76 into open position the pipe or bar 84 is removed from the spring bracket 86 and the entire tail gate is moved into generally parallel relation to the side wall 34. The tail gate is then slid forwardly along 35 the wall 34, the rail 84 sliding over the pulley or roller 87. When in the overlapped position shown in Figure 1 of the drawings, a spring clamp 91 on one end of the bar 84 is resiliently engaged with the forward end of the rail or pipe 89, thus 40 supporting the tail gate in position extending along the side wall of the barge.

Most of the operation of my device will be apparent from the foregoing description. The tail gate is in position extending across the rear end 45 of the body with the pipe or rail 84 engaged in the spring clamp 86. A pin may extend through the ends of the spring clamps 86 and 91 if desired to make sure these clamps will not become accidentally disengaged. The ends of the 50 chain 81 are engaged in the brackets 83 to hold the tail gate firmly closed.

The barge is now filled with hay or straw and many tons of this material may be loaded onto the barge, the barge being substantially built and 55 of considerable size. The draw bar 59 is attached to the draw bar connection 92 of the tractor B during this operation. When filled the barge A is moved by the tractor B to a suitable position for unloading. In unloading the barge A a universal 60 extendable and contractable connection 93 is provided between the power take-off of the tractor B and the forwardly projecting end 94 of the transmission 25. Thus by operating the power take-off of the tractor the transmission may be driven.

65 In unloading the barge the tail gate is first moved into open position and fastened in this position. Both of the legs 73 are then unhooked and pivoted down into contact with the ground. The locking lever 67 is unlatched from the angle 70 64. The tractor is then backed in a reverse direction, the legs engaging the ground and gradually tilting the front end of the barge upwardly and the rear end of the barge downwardly. This action is continued until the rear end of the barge 75 strikes the ground or is extremely close thereto.

The locking lever 67 is then engaged with the angle member 64 to hold the barge tilted.

The power take-off is then operated and the transmission 25 properly actuated to move the pusher 50 toward the rear of the barge two or three feet to loosen the load upon the barge. The tractor is then started into movement forwardly and the barge is pulled ahead until the load is almost off the rear end of the barge. During this operation the pusher 50 may or may not be in operation as desired.

When the load is almost removed from the barge the forward movement of the barge is stopped and the pusher is moved toward the front end thereof or returned to its forward position. The locking lever 67 is next disengaged from the angle 64, tending to allow the barge body to tilt into horizontal position. Upon slow forward movement of the tractor the barge will slowly tilt into horizontal position resting upon the draw bar 59. The body may be locked by the lever 67 in this position.

From an examination of Figure 4 of the drawings it will be obvious that I provide an opening 95 in the forward wall 40 of the barge. This aperture allows the tractor operator to have a clear view of the position of the pusher 50 so as to stop operation of the chains 47 and 49 when the pusher has reached its forward extreme position.

I have found my barge to be a great time and money saver, particularly when grain is harvested with a header. The stack may be built up in the barge and delivered thereby to a desired spot. By harvesting in this way considerable money is often saved as the grain may be harvested at an earlier date with a header, thus preventing injury to the grain and straw due to hail, or the like. It should further be noted that the chains 47 and 49 are positioned above the level of the floor 31 and tend to move the entire load. Weight upon the chains merely tightens the same.

The barge may be conveniently used for building stacks of hay, straw, corn bundles and many different types of grain bundles. My barge works excellently for dumping bundles near the feeder of the threshing machine when it is so desired.

In accordance with the patent statutes, I have described the principles of construction and operation of my barge, and while I have endeavored to set forth the best embodiment thereof, I desire to have it understood that obvious changes may be made within the scope of the following claims without departing from the spirit of my invention.

I claim:

1. A barge comprising a body, a cross member supporting said body near the center thereof, axially aligned wheels at opposite ends of said cross member, legs on said body pivotally movable into engagement with the ground, axially aligned pivots parallel to the wheel axes connecting one end of each leg to said body, said legs being of sufficient length to tilt said body about said wheel axes when pivoted into engagement with the ground and upon longitudinal movement of the barge in a direction to pivot the legs toward vertical position.

2. A barge comprising a body, side walls on said body, a removable end wall thereupon, axially aligned wheels tiltably supporting said body to tilt the end of said body having said removable end wall toward or away from the ground, a pair of

legs pivotally supported to the other end of said body, axially aligned pivots parallel to the wheel axes connecting one end of each leg to said body, said legs being pivotally movable into engagement with the ground, said legs engaging the ground and tilting said body upon longitudinal movement thereof in a direction to pivot the legs toward vertical position.

3. A barge comprising a barge body, a pair of opposed axially aligned wheels supporting said body for forward or rearward tilting motion, a draw bar pivotally connected to said body, axially aligned pivots parallel to the wheel axes and spaced forwardly a relatively short distance therefrom connecting said draw bar to said body, legs on said body engageable with the ground and operable on longitudinal movement of the body to tilt the same relative to said draw bar, axially aligned pivots parallel to the wheel axes connecting one end of each leg to said body, and means for locking said body in fixed angularly adjusted position relative to said draw bar.

4. A barge including a body, wheels supporting said body adjacent the mid-point thereof, a draw bar pivotally connected to said body, said body being tilttable relative to said draw bar, legs pivotally carried by said body and pivotally engageable with the ground which are operable on longitudinal movement of the body to tilt the same relative to the draw bar, and locking means for locking said body from pivotal movement relative to the draw bar in any selected tilted or horizontal position.

5. A barge including a body, wheels supporting said body adjacent the mid-point thereof, a draw bar pivotally connected to said body, said body being tilttable relative to said draw bar, legs on said body pivotally engageable with the ground and operable on longitudinal movement of the body to tilt the same relative to the draw bar, and locking means for locking said body from pivotal movement relative to the draw bar in any selected tilted or horizontal position, said locking means including an arm transversely pivoted to said draw bar, a bracket on said body through which said arm may slide upon tilting movement of said body, and means for locking said arm in adjusted relation to said bracket.

EDGAR T. STROM.
